UNITED STATES PATENT OFFICE.

ROBERT O. HENDRICKSON AND KINSEL EARL MOREE, OF RACINE, WISCONSIN,
ASSIGNORS, BY MESNE ASSIGNMENTS, TO J. I. CASE PLOW WORKS COMPANY,
OF RACINE, WISCONSIN, A CORPORATION OF DELAWARE.

FLANGING MACHINE.

1,420,427.

Specification of Letters Patent. Patented June 20, 1922.

Application filed July 26, 1919. Serial No. 313,457.

To all whom it may concern:

Be it known that we, ROBERT O. HENDRICKSON and KINSEL EARL MOREE, citizens of the United States, residing at Racine, in the county of Racine and State of Wisconsin, have invented certain new and useful Improvements in Flanging Machines, of which the following is a specification.

For certain forms of tractor and the like, ground wheels are adopted having broad rims of sheet steel, connected to the hubs by suitable metal spokes and provided on their outer peripheries with spokes or projections for gripping the ground or roadway over which the wheels travel. Such rims are commonly cylindrical bands and in order to stiffen them they are sometimes provided or formed with inwardly extending flanges at their respective edges. The present invention relates to a machine which receives a plain cylindrical band of sheet metal of sufficient width to provide the cylindrical tread and flanges of the desired depth and bends the edges of the bands to form said flanges. The machine comprises a rotating mandrel or support upon which the cylindrical band which is to form the rim is secured from within and a pair of rollers so mounted in respect to the mandrel that they may be fed inward against the band upon the latter to gradually bend the edges which are to constitute the respective flanges inward into parallel planes. With the subsequent operations of providing the rim with spokes and spuds the present invention has nothing to do.

In the accompanying drawings we have shown, and in the following specification described in detail a preferred form of our invention. It is to be understood, however, that the specific disclosure is for the purpose of exemplification only and that the scope of the invention is defined in the following claims in which we have endeavored to distinguish it from the prior art so far as known to us without, however, relinquishing or abandoning any portion or feature thereof.

Referring now to the accompanying drawings, Fig. 1 is a plan, partly in horizontal section, of a flanging machine embodying our invention; Fig. 2 is a side elevation thereof; Fig. 3 a vertical section on the plane

of the broken line 3—3 of Fig. 2, and Figs. 4 and 5 horizontal sections of a detail showing respectively parts in different positions which they occupy during the bending or flanging operation. The rotating mandrel may be of any preferred construction provided that it affords means for firmly holding the bands 7, Fig. 2 from which the rims are to be formed thereon and permits of the removal of the rims after the flanges have been formed. We have shown the mandrel as comprising an integral or rigid core 8 having a rim 9 and spokes 10 connected to a suitable hub. This core may be cast integral if desired. At suitable intervals about its periphery the core is provided with radially movable shoes 11 which are adjusted by means of screw bolts 12 tapped into lugs 13 formed or provided upon the integral core of the mandrel. As seen in Fig. 2 there are three of the segmental shoes each of which is supported at its center by one of the adjustable screw-bolts 12. Adjacent ends of the segmental shoes are supported by blocks or bars 12^a which are adjusted inwardly and outwardly by means of screws 12'. The ends of the segments are rabbeted to provide bearings for the bars 12^a and, in the position shown in Fig. 2 in which the segments are adjusted outwardly to support a tire 7 the ends of adjacent shoes are spaced apart as at *xx* Fig. 2. Each of the segments is provided near its center with an inwardly projecting lug *b* which, bearing against the corresponding lug 13 on the mandrel, supports the segment against circumferential movement. Sufficient adjustment is provided so that the shoes may be pressed firmly against the inner surface of the band to secure the latter in proper position upon the mandrel prior to the flanging operation and withdrawn when the flanging operation is completed a sufficient distance to permit the flanged rim to be removed axially off the mandrel. The mandrel is journaled upon a rigid frame and provided with rotating mechanism, the particular form of the mounting and driving mechanism being immaterial provided the required strength and power is furnished. In the particular device illustrated we have shown the frame as comprising parallel side members 14, 15 and end members 16, 17 formed of heavy sec-

tions of I-beams (see Fig. 2) and the mandrel is journaled transversely on the frame, the shaft 18 of the mandrel being journaled in housings 19, 20 on the side members 14, 15 of the frame respectively. The shaft 18 is provided with a gear 21 which is driven by a pinion 22 upon jack shaft 23 which is likewise journaled in the frame and carries a gear 24 which is in turn driven by a pinion 10 25 on shaft 26 of pulley 27. The last named element is driven by a belt from any suitable source of power. When the machine is in operation the mandrel is driven from the pulley through the train of reducing gear 15 described, at a slow speed.

The bending of the flanges is gradually effected, as the mandrel revolves, by a pair of rollers 28, 29 which are so mounted in the frame as to be capable of being fed slowly 20 inward against the flange portions of the band upon the mandrel, their first contact therewith being while they are almost axially parallel to the shaft of the mandrel (see Fig. 5) from which position they are slowly 25 swung to the position perpendicular to the axis of the mandrel (see Fig. 4). In order that the rollers may turn or spin the curved corners on the rim shown in Fig. 4 it is necessary that they swing on arcs the centers of 30 which are concentric with the said curved corners, and it is a further requisite that prior to the beginning of the spinning or bending operation the rollers be withdrawn to permit the ready application of the rim 35 band to the mandrel, as shown in Fig. 1. With this in view a carriage 30 upon which the rollers are borne is dovetailed to slide 40 upon a guide 31 upon which it may travel toward and from the mandrel, said carriage comprising a top plate 44 and a depending member 32 which is engaged by a screw 33 carried in a heavy standard 34, the screw being for the purpose of adjusting the carriage along the guide in an obvious manner, 45 and extending loosely through the frame member 16.

Obviously, in order that the rollers may form the small arc 35 at the junction of the flanges and the tread of the tire, they must 50 be swung about axes respectively concentric with said curves. For this purpose the rollers 28, 29 are horizontally journaled respectively in the upper end of swinging arms 38, 39 which are pivoted at their lower ends as at 40, 41 in a horizontal plate 42 carried by the depending member 32, the construction of this depending member and plate being such that when it is carried forward by means of the screw 33, the axes of rotation 55 of the respective arms are so located as to permit the rollers carried thereby to swing in the arc previously described. The depending member is partially supported by a roller 42^a which travels on track 43 as the 60 carriage is fed toward or away from the

mandrel. In order to support the rollers during their swinging movement to form the corners of the tire, the top plate 44 of the carriage is provided with a pair of arcuate tracks 45, 46, concentric with the pivots of the respective arms and against which the upper ends of the latter bear. The arms may be provided with anti-friction rollers at these respective points if desired. In order to swing the arms about their pivots 70 during the spinning operation a pair of links 47, 48 are pivoted to the upper ends of the respective arms and to a common yoke 49 which may be forced inward toward the mandrel by means of a screw 50. The latter may be driven by a hand-wheel or power mechanism, as desired, but we have shown in the drawings a hand-wheel 51 for the purpose.

In operation the carriage carrying the 85 rollers are withdrawn a convenient distance from the mandrel, and the latter with its shoes retracted receives the band or cylinder which is to form the tire. The shoes are then fed outward to firmly support the band. 90 The carriage with its rollers then fed inward by the screw 33 until the rollers engage the edges of the band on the mandrel and, the mandrel being in the meantime revolved, 95 bend them to the position shown in Fig. 5. The hand-wheel is then turned to drive the yoke 49 inwardly toward the mandrel and the links connected to said yoke and the roller-carrying arms then slowly swing the latter about the mandrel and tire until they 100 reach the position shown in Fig. 4. The treatment of the tire is then completed and the parts are restored to the normal or retracted position. The tire is then stripped off the mandrel by withdrawing the shoes 105 from contact with said tire.

We claim:

1. In a device of the class described, a frame, a mandrel revolvably mounted on the frame and adapted to receive and hold on its periphery a band of metal to be flanged with the edges thereof extending beyond the mandrel, a guide on the frame extending substantially radially of the mandrel, a carriage mounted to slide on the guide, means for adjusting the carriage on the guide toward and from the mandrel, a depending member 110 on the carriage, a pair of arms 38, 39 pivoted at their lower ends on said depending member, arcuate guide plates 45, 46 on the carriage concentric with the axes of the respective arms and against which the upper ends of the latter bear, rollers 28, 29, journaled on horizontal axes in the upper ends of the respective arms, and means 115 for swinging the arms and the rollers carried thereby about the axes of the respective arms.

2. In a device of the class described, a frame, a mandrel revolvably mounted on the 130

frame and adapted to receive and hold on its periphery a band of metal to be flanged with the edges thereof extending beyond the mandrel, a guide on the frame extending substantially radially of the mandrel, a carriage mounted to slide on the guide, means for adjusting the carriage on the guide toward and from the mandrel, a depending member 32 on the carriage, a pair of arms 38, 39 pivoted at their lower ends on said depending member, arcuate guide plates 45, 46 on the carriage concentric with the axes of the respective arms and against which the upper ends of the latter bear, rollers 28, 29 journaled on horizontal axes in the upper ends of the respective arms, and means for swinging the arms and the rollers carried thereby about the axes of the respective arms comprising links 47, 48, pivoted to said arms, 20 a yoke 49 to which said links are pivoted and an adjusting screw 50 connected to said yoke

for moving the same toward and from said mandrel.

3. In a device of the class described, a mandrel adapted to receive a cylindrical band and to be slowly rotated on a horizontal axis, a pair of arms pivoted at points substantially lower than the mandrel for a swinging movement in a horizontal plane, a pair of rollers carried by the respective arms at substantially the level of the axis of the mandrel, guides for the respective arms substantially in the horizontal plane of said rollers and adapted to support said arms against the pressure of said rollers, means for swinging the roller-carrying arms about their respective axes comprising a screw, a nut movable on said screw, and links connecting said nut to the respective arms.

ROBERT O. HENDRICKSON.
KINSEL EARL MOREE.
